[57] **CLAIM**

The ornamental design for a combination flashlight and spanner wrench, as shown and described.

DESCRIPTION

FIG. 1 is a side elevational view of a combination flashlight and spanner wrench showing my new design, the elevational view from the opposite side being substantially a mirror image;

FIG. 2 is a top plan view thereof;

FIG. 3 is a front end elevational view thereof;

FIG. 4 is a rear end elevational view thereof; and,

FIG. 5 is a bottom plan view thereof.

FIG. 2

FIG. 1

FIG. 3

FIG. 4

FIG. 5
